COLLAPSIBLE CRATE

William A. Thimm, Milwaukee, Wis.

Application July 28, 1937, Serial No. 156,122

2 Claims. (Cl. 220—6)

This invention relates to collapsible crates for poultry and the like.

The general aim of the present invention is to provide a sturdy, economical crate which can be quickly folded into a small part of its original bulk for convenience in transporting and handling the same.

Another object is to provide such a crate in which the various members shall coact to brace each other and to produce a strong expanded structure.

Another object is to provide a crate which shall collapse easily and with a minimum of interference by the members.

Other objects and advantages will appear, expressed or implied, from the following description of the illustrative embodiments of the present invention.

In the accompanying drawings:

Figure 1 is a perspective view of a poultry 20 crate constructed in accordance with the present invention.

Fig. 2 is a perspective view of the poultry crate when collapsed.

Fig. 3 is a partial end view of the poultry 25 crate.

Fig. 4 is a partial side view of the crate.

Fig. 5 is a partial transverse sectional view taken on the line 5—5 of Fig. 4.

Fig. 6 is a partial longitudinal sectional view taken on the line 6—6 of Fig. 3 with the folded position of the members shown in shadow.

Fig. 7 is a partial longitudinal sectional view along the same line as Fig. 6, showing the crate in the collapsed condition of Fig. 2.

Fig. 8 is a partial view of the top of the crate.

Fig. 9 is a bottom view of the crate on a reduced scale.

The crate illustrated in the drawings is erected upon a bottom portion 11 formed in the shape of a tray. It consists of longitudinal and transverse bars 12 and 13 joined in a grid-like formation, and having upturned end portions 14 and 15, respectively, joined to end bars 16 and side bars 17 forming the rim of the tray. The grid-like bottom portion is preferably lined with a sheet metal tray 18.

Hinged to either side of the bottom portion 11 are side panels 19, each formed of longitudinal bars 20 supported by vertical bars 21. These side panels are joined to the bottom portion in a novel manner, the vertical bars 21 having their lower ends bent into loops 22 surrounding the side rail 17 to form hinges joining the side panel to the base.

The ends of the crate are each formed by two panels 23 and 24. Each end panel consists of cross-bars 25 supported by vertical bars. The lower panel 23 has top and bottom rails 26 and 27 to which the vertical bars 28 are joined. The upper panel 24 however has only a top rail 29, and in place of a bottom rail the vertical bars 30 are formed into loops 31 surrounding the top rail 26 of the lower panel to hinge the panels 10 together in a manner similar to the side panel hinges described above. Similar loops 32 are formed on the upturned ends 14 of the longitudinal bars 12 of the bottom tray, the ends 14 being extended above the end rail 16 for this purpose. These loops 32 engage about the lower bar 27 of the lower end panel 23, securing the end panels to the crate.

The ends of the crate serve as supports for the top 33, which consists of longitudinal bars such as 34, braced by cross-bars, such as the center bar 35, the intermediate bars 36, and the end bars 37. The ends of the longitudinal bars (such as 34) are extended beyond the end bars 37 and formed into the loops 38 surrounding the top rail 29 of the upper end panel 24, thus hinging the top 33 to the end panel.

A transverse partition 39 depends from the center of the top 33. This partition comprises a grid-like formation of vertical bars 40 and horizontal bars 41. Some of the vertical bars, such as 42, are extended above and below the grid formation, carrying at their lower ends the lower cross rail 43, and at their upper ends having loops 44 about the center bar 35 of the top panel, 35 to hinge the partition to the top panel.

It may readily be seen from the drawings that the ingenious hinged arrangement allows the crate to be easily collapsed. The partition 39 is first drawn up against the top 33, as shown in Fig. 6, and the side panels 19 swung into the crate, as shown in Fig. 5. The hinged end panels 23 and 24 then function like a toggle, folding inwardly, as shown in Figs. 6 and 7, and allowing the top 33 to descend upon the folded lower parts.

It should be noted that the line of hinges of each folding part is so placed that there will be no interference in the folding operation. Thus the side hinge loops 22 are placed above the edge of the tray 18, so that the side panels may fold over the top of the tray. Likewise, the end hinge loops 32 are situated above the line of the side hinges 22 so that the end panels may fold inwardly above the side panels without interference therewith.

As the crate is unfolded again, it may readily be seen how the ingenious arrangement of hinged parts allows each to support and brace the other. Lifting the top panel 33 straightens out the end panels 23 and 24, which will support the top securely so long as they are maintained in a straight line. The side panels 19 then swing upward between the panels at each end, which are formed to extend slightly beyond the vertical position of the side panels, so that the side panels 10 prevent inward collapsing of the end panels. Further outward movement of either sides or ends is prevented by clips 45, attached to the vertical side bars 30 of the end panels 24, in such position that the vertical end bar 21 of 15 the side panels enters the clips when the side panel is raised.

After the side panels are in place, the center partition 39 may drop into place between the side panels, providing a strong brace member 20 effectively preventing inward swinging of the sides, and supporting and bracing the crate. To impart strength to the partition as a bracing member, the vertical bars 40 are spaced relatively closely together, and securely fastened to 25 the cross bars 41. A spring clip 46 located on the bottom of the tray 18 receives the bottom rail 43 of the partition and holds it against undesired further movement in either direction.

There should be provided openings to give 30 access to the interior of the crate, and means for closing the same. The structure shown in the drawings has been found satisfactory. Openings 47 are provided in the top panel 33 on either side of the partition 39 by removing from 35 a number of central longitudinal bars 48 the portion between the central transverse rail 35 and the adjacent intermediate rail 36. A cover 49 for these openings is in the present case 40 formed of longitudinal bars 50 corresponding to the shortened bars 48, and transverse bars 51 and 52 supporting them at either end. Each of the transverse bars 51 and 52 has its ends 45 formed into loops 53 surrounding the longitudinal bars 54 adjacent the opening, so that the cover is slideable along the bars 54 over the opening.

It will be noted that the crate has been designed to slide freely along a supporting surface. The longitudinal bars 12 of the bottom of the 50 crate are placed beneath the transverse bars 13, thus forming skids upon which the crate may readily slide. All connections between the bars 12 and other pieces are raised above the level of the bars, and the ends of the bars are 55 upturned so that each bar presents a continuous surface having no projections or interruptions to interfere with free sliding thereof.

Various changes may be made in either embodiment of the invention hereinabove specifically described without departing from or sacrificing the advantages of the invention as defined in the appended claims.

I claim:

1. In a collapsible poultry crate the combination of a base comprising a grid-like tray formed of longitudinal and transverse wire bars having upturned ends, a sheet metal tray mounted in said base and forming a bottom for said crate, a top for said crate comprising longitudinal wire bars and connecting means therefor, lower and upper end panels comprising transverse bars and connecting means therefor, said upper and lower end panels being hinged together and to said top and said base to form toggle end members for said crate extensible into erect position between said top and base members, side panels comprising longitudinal and vertical wire bars, said side panels being hinged to said base at their lower edges and being extensible between said end panels, said toggle end panels having means interengageable with said side members to thereby retain said end members in upright position, and a central partition comprising transverse and vertical wire bars, said partition being hinged to said top member and being moveable into upright position between said side panels to thereby retain said side panels in upright position, and a spring clip in the bottom of said crate for releasably retaining said crate in unfolded condition.

2. In a collapsible poultry crate, the combination of a base comprising a grid-like tray formed of longitudinal and transverse wire bars having upturned ends, the ends of said longitudinal bars forming loops and the ends of said transverse bars carrying a longitudinal bar, lower end panels comprising transverse bars and connecting means therefor, the lower of said bars being hinged in the loops on the upturned ends of the longitudinal base members, upper end panels comprising transverse bars and connecting means therefor, said upper end panels being hinged to said lower end panels to form toggle end members for said crate, a top for said crate comprising longitudinal wire bars and connecting means therefor, said longitudinal bars having end loops engaging the upper bar of said upper end members to form a hinge therefor, said toggle end members being extensible into erect position between said top and base members, side panels comprising longitudinal wire bars and vertical connecting bars, said vertical bars having at their lower ends loops engaging the longitudinal bar carried by the ends of the transverse base bars, to thereby hinge said side panels to said base, said side panels being extensible between said end panels, and a central partition comprising transverse wire bars and vertical connecting bars having looped ends engaging said top member to hinge said partition, said partition being moveable into upright position between said side panels to thereby retain said panels in upright position.

WILLIAM A. THIMM.
